[57] CLAIM

I claim the ornamental design for a wardrobe/TV cabinet, as shown and described.

DESCRIPTION

FIG. 1 is a front elevational view of a wardrobe/TV cabinet showing my new design;

FIG. 2 is a left side elevational view, the right side being a mirror image thereof;

FIG. 3 is a front elevational view with the doors in open position; and,

FIG. 4 is a front elevational view of FIG. 3 with a TV turntable.

The top and rear of the cabinet not shown form no part of the claimed design.
